United States Patent Office.

C. O. CROSBY, OF NEW HAVEN, CONNECTICUT.

Letters Patent No. 101,354, dated March 29, 1870.

IMPROVEMENT IN MACHINERY FOR MAKING PAPER BOXES.

The Schedule referred to in these Letters Patent and making part of the same.

To all whom it may concern:

Be it known that I, C. O. CROSBY, of New Haven, in the county of New Haven and State of Connecticut, have invented a new Machine for Making Paper Boxes; and I do hereby declare the following, when taken in connection with the accompanying drawings and the letters of reference marked thereon, to be a full, clear, and exact description of the same, and which said drawings constitute part of this specification, and represent in—

Figure 1, a top view;

Figure 2, an end view;

Figure 3, a side view;

Figures 4, a partial sectional view;

Figures 2', 5, 6, and 7, detached views to illustrate the operation of the machine; and in

Figures 8, 9, 10, 11, and 12, construction of the box as produced by the machine.

This invention relates to an improvement in the construction of a machine for making paper boxes, especially adapted to the box invented by me, and for which I have filed an application for Letters Patent of the United States, the object being to form, automatically, a box from paper or similar material, which, when folded, is secured together during the process of folding, so as to dispense with the use of paste.

To enable others skilled in the art to construct and use my invention, I will fully describe the same as illustrated in the accompanying drawings.

I will first describe the box which it is designed to produce by this machine.

From a sheet of paper or board, I cut into the form seen in fig. 10, the broken lines indicating where the paper is to be turned to form the angles, and where the folds are to be made. The angles 1, 1, 1, 1 are cut away as a matter of convenience, and not of necessity, so that the portion 2 will be not more in length than one-half the width of the box. The paper is slitted on the lines 3, 3, 3. Then the sides 4, 4, with their connected parts 2, 2, are turned up, and the parts 2, 2 turned inward, to form a right angle. Then the parts 5, 6 are turned up at each end, so that the part 6 rests against the parts 2, 2. Then the part 5 is turned down over the parts 2, 2 into the box, as seen in figs. 1 and 2, it being of sufficient depth to extend to the bottom of the box. Then an indentation, 7, is made in the bottom at the end of part 5, as seen in figs. 1 and 2, which holds the two parts 5 firmly in place, and securely binds the box together.

Boxes as heretofore constructed and secured together by paste or glue necessarily gather more or less moisture, which, particularly for matches, renders such boxes objectionable. This objection is overcome by my box.

I will now proceed to describe the machine for producing this box.

A is the bed-plate of the machine, upon which, in proper bearings, B, rests the driving-shaft C, from which the several parts of the machine are operated.

In a standard, D, a slide, D¹, is arranged, operated by a cam, D², through the lever D³.

The paper or sheet from which the box is to be formed is passed through an opening, a, in the standard D, the lower surface of the said opening and the under surface of the slide D¹ being provided with a means for creasing the paper on the lines where the angles or folds are to be made, and also with dies, 7, shown in solid black, fig. 1, for cutting away the necessary waste paper, as and for the purpose before described.

The slide, with its dies, operates upon the end of the sheet, as in fig. 8, cutting away the part 1, 1, which forms one-half of two boxes. The sheet, after this operation, is fed along until the proper distance for again cutting and creasing the paper.

When the second operation is performed, to cut and crease the paper, as in fig. 9, cutters d, attached to the slide D, (see figs. 1 and 2,) cut the slits 3, (see fig. 9,) while, at the same time, a shear, e, upon a lever, E, operated by a cam, E', cuts off the paper at the center of the space 1, 1, as denoted by the blue line, fig. 8, leaving the end of the sheet in the form seen in fig. 9. From this point the paper is automatically fed, by a revolving feed upon a shaft, F, to which an intermittent movement is given by a cam F¹, through a lever, F², and pawl F³.

When the paper has been cut as in fig. 9, it is fed along and operated upon as before, the shear e cutting off, at the blue line, fig. 9, the blank, as seen in fig. 10, which is in proper form for folding, and at the time the shear separates the blank from the sheet, the blank has passed beneath the slide I in the standard I¹, the said slide operated by the cam I² through the lever I. The said slide I, descending upon the paper, presses it down between the two side dies J, (see fig. 2.) A corresponding follower, L, operated by a cam, L through a lever, L², beneath the machine, grasps the paper between the slide I and follower L in its descent between the dies J, J. This turns up the two sides 4 and the parts 2, 2 connected thereto.

When the sides have thus been turned up, the transverse slides P, P, to which the folders P¹ are attached, (see fig. 5,) are forced inward by the action of the cam P², through the lever P³ and its connection P⁴, which turns the parts 2 inward. Then the slide I again descends, carrying the blank down between the two end dies N, N, (see fig. 4,) which turn up the two ends 5, 6, passing down until the top of the box comes flush with the top of the dies N. Then the central portion I¹ of the slide, which is operated by an independent cam, I², through a lever, I³, remains stationary down, as seen in fig. 6, while the other portion

I of the slide rises, the part I⁵ holding the box (so far as it is folded) in proper position. Then, when the part I has sufficiently risen, the two folders R R, operated by a crank, R¹, through a sliding bar, R², as seen in fig. 1, pass inward, and turn down the part 5 of the blank. Then the folders R withdraw, and the slide I again returns, as in fig. 7, pressing the parts 5 of the box down, as in fig. 12.

The box, after being thus folded, is pressed further down, until, at each end, or upon each edge of the slide I, a punch, L¹, (see fig. 5, and in broken lines, fig. 7,) presses up into the bottom of the box, so as to indent, as at 7 7, which completes the box; and, when the slide around which the box is folded is withdrawn, the cam S, through a lever, S¹ and a slide, S², (see fig. 2,) throws the box from the top of the slide L. A second box follows in like manner, and so continues making and completing the boxes.

The machine may be adjusted for boxes of different sizes in similar manner as other automatic machines, as it may also for boxes of different forms; and covers for the boxes are produced in the same manner.

Having fully described my invention,

What I claim as new and useful, and desire to secure by Letters Patent, is—

1. The slide D¹, provided with the creasing apparatus and dies 7, operating as and for the purpose set forth.

2. In combination with the slide D¹, arranged to operate as described, the cutters d, for slitting the blank, as and for the purpose specified.

3. In combination with the slide D¹ and cutters d, a feeding device arranged so as to carry the blank into the machine, substantially as set forth.

4. In combination with the slide D¹, operating as described, and the cutters d, the shear e, all operating together as and for the purpose specified.

5. The slide I, combined with the follower L and the two side dies J, operating together as and for the purpose specified.

6. In combination with the slide I, follower L, and dies J J, the folders P¹, operating as and for the purpose specified.

7. In combination with the slide I, follower L, and folders P¹, the dies N N, operating as and for the purpose specified.

8. In combination with the slide I, follower L, folders P¹, and dies N N, the auxiliary slide I⁵ and the folders R R, all operating together as and for the purpose specified.

9. In combination with the slide I and follower L, the punches L¹, operating as and for the purpose set forth.

10. In combination with the slide I, follower L, and folders P¹ and R, the slide S², arranged so as to throw the box from the machine, substantially as set forth.

C. O. CROSBY.
